(57) **CLAIM**

The ornamental design for nosepieces for spectacle frames, as shown and described.

DESCRIPTION

FIG. 1 is a front view of the nosepieces in accordance with my new design;

FIG. 2 is a right symmetrical view thereof;

FIG. 3 is a back view thereof;

FIG. 4 is a perspective view thereof; and,

FIG. 5 is an overall view for which only the protection of the nosepieces is claimed.

The novelty of the design resides in its shape.

A single nosepiece is shown in FIGS. 1-4 for ease of illustration only.
